VEGETABLE SLICER AND GRATER

Clyde W. Prickett, Santa Monica, Calif.

Application April 3, 1933, Serial No. 664,176

8 Claims. (Cl. 146—152)

The object of my invention is to provide a vegetable slicer and grater which is simple, durable and comparatively inexpensive to manufacture.

5 A further object is to provide a slicer for vegetables, fruit or the like having interchangeable knives so that coarse or fine slices can be taken, or grater knives of coarse or fine cut, as desired, may be substituted for the knives, the apparatus for providing for the interchange of knives being readily operable for this purpose.

10 A further object is to provide a vegetable slicer and grater in which a hopper has substantially vertical walls to prevent friction of the vegetables thereon, so that the vegetables can readily feed down into slicing position, the slicing blade carrying a slicing knife, arranged to travel at an undershot angle so that the weight of the vegetable is imposed on it, the hopper being substantially V-shaped so that the last particle of the vegetable being sliced can be operated upon without leaving any coarse pieces unsliced.

15 Still a further object is to provide a slicer of simple construction made from wire and sheet metal, the device comprising a rectangular wire frame with a sheet metal hopper secured to it by edges of the hopper encircling the frame, a slicing blade being slideable along the frame and having guide edges partially encircling the edges of the hopper which encircle the frame to provide the means for slidably mounting the blade relative to the hopper.

20 Still a further object is to provide a removable leg for the slicer which can be associated therewith during the slicing operation and readily disconnected therefrom when the slicer is not in use, this being especially desirable when the slicer is boxed for shipment.

25 Still a further object is to provide stops for limiting the movement of the slicer blade, the blade being movable rather than the hopper as in some types of slicers and thus eliminating any danger of cutting the operator's fingers.

30 Another object is to provide one of the stops in the form of a spring hook so that it first arrests the movement of the slicer blade and then stops it, the other stop being arranged so that it can be sprung to position allowing disconnection of the slicer blade from the hopper and its frame for washing purposes or for changing blades.

35 With these and other objects in view my invention consists in the construction, arrangement and combination of the various parts of

my device, whereby the objects contemplated are attained, as hereinafter more fully set forth, pointed out in my claims, and illustrated in the accompanying drawings, in which:

Figure 1 is a vertical sectional view through a vegetable slicer embodying my invention. 5

Figure 2 is a rear elevation of the slicer blade, the upper end being broken off to conserve space on the drawings.

Figure 3 is a sectional view through the hopper, slicing blade and slicing knife as taken on the line 3—3 of Figure 2. 10

Figure 4 is a sectional view similar to the central portion of Figure 1 showing the slicer blade in a raised position and a stop hook 15 sprung to disengaging position.

Figure 5 is a perspective view of the slicing knife.

Figure 6 is a front elevation of a grater knife. 20

Figure 7 is a sectional view on the line 7—7 of Figure 6.

Figure 8 is a central sectional view through a modified form of hopper construction; and

Figure 9 is a view similar to the upper portion of Figure 8 showing a hinged door for the hopper removed to illustrate the connection of a spring for the door to the hopper. 25

On the accompanying drawings, I have used the reference numerals 10, 12 and 14 to indicate side members, a lower cross bar and an upper cross bar, respectively, of a substantially rectangular wire frame. A hopper is comprised of side walls 16 and a front wall 18, each of which is substantially vertical. The rear edges of the side walls 16 encircle the side members 10 of the frame, as shown in Figure 3. 30

In order to retain the hopper against longitudinal movement relative to the wires 10, I provide a cross bar 22 at the lower edge of the wall 18, the cross bar having depending ends 24 soldered or otherwise secured to the wires 10. The cross bar 22 serves as a reinforcement and terminates the lower edge of the hopper at the proper position for the slicing knife to just clear, as will hereinafter appear. 40

For supporting the hopper, I provide a substantially U-shaped leg member A having a cross bar 26 and terminal ends 29. The terminal ends are adapted for threading through eyes 31 which are formed by slitting the sides 16 of the hopper and bending alternate sections between the slits in opposite directions. 45

I provide a substantially flat cutting blade 28 having side edges 30 partially encircling the edges 20 of the hopper. This arrangement pro- 50

vides for slidably guiding the slicing blade 28 relative to the hopper and places the blade in position to form one wall of the hopper. The blade 28 has a handle portion 29.

5 The hopper is provided with a substantially rectangular opening defined by the lines 32, indicated in Figure 2, from which lips 34 and 36 extend.

10 Lines 38 represent the edge of a rearward depression in the blade 28 to receive a slicing knife 40. The slicing knife 40 has lips 42 to engage the lower edge of the opening 32 to retain the lower edge of the slicing knife in position relative to the slicing blade. The lips 36 serve as shoulders 15 to limit swinging movement of the knife to position alined with the blade.

15 To retain the knife in position and yet permit its ready removal, a turn button 41 is provided. It is pivoted at 43 to the blade 28. It has a cut-20 away edge 44 which, when in the dotted line position of Figure 2, will permit removal of the knife 40. When in the full line position, however, it is swung in front of a depressed portion 46 of the knife 40 to retain the knife in alined 25 position.

25 The knife is provided with a gauge edge 48 and a sharpened cutting edge 50. The gauge edge first engages the vegetable being sliced and the elevation of the cutting edge 50 above the 30 plane of the knife then determines the thickness of the slice. I contemplate the provision of different knives for different thicknesses of cut and that is why I make the knives so readily removable.

35 In sliding the slicing blade downwardly, it is desired to have a stop which first arrests its movement and then positively stops it. I provide this in the form of a U-shaped spring 52 having a hook portion 54. The spring first frictionally engages the cross bar 14, as shown in 40 Figure 1, to arrest the sliding movement of the slicing blade and after the blade is moved slightly further, the hook 54 serves as a positive stop.

45 To stop the upward movement of the slicing blade, I provide a U-shaped spring 56 on the lower edge thereof having a hook portion 58 to engage the cross bar 22. As shown in Figure 4, the hook can be sprung to a position where it does not engage the cross bar, whereupon the 50 slicing blade may be removed for washing purposes or for changing the knives therein. The spring 56 prevents the blade 28 from allowing vegetables to fall out of the hopper.

55 It will be noted in Figure 3 that the cutting edge 50 of the knife extends the entire width of the hopper so that no ridges are left at the sides of the vegetable being sliced to prevent its subsequent feed to the knife. This is accomplished by providing reinforcing flanges 60 for 60 the sides of the knife (see Figures 2 and 5) so that the knife does not have to extend sidewise beyond the ends of the slot therein between the gauge edge 48 and the knife edge 50. The flanges 60 extend at substantially right angles to 65 the plane of the knife.

70 In Figure 6, I have shown a knife 40a having grater cutting edges 50a rather than a knife edge 50 as shown in Figure 5. Different blades with larger or smaller grater edges and depressions can be provided so that the device can be universally used for both fine and coarse grating or slicing.

75 In Figure 8, I have illustrated a modified form of construction in which the wall 18a of the hopper is hinged on the cross bar 14. It is con-

strained to move toward the slicing blade by springs 62 having their ends 64 anchored along the edges of the hopper walls 16a, as shown in Figure 8.

80 A handle 65 is provided for retracting the wall 18a for inserting a vegetable 66, whereafter the wall is permitted to engage the vegetable and during the reciprocations of the cutting blade, will feed the vegetable into the blade. The wall 18a will finally assume a position adjacent the 10 cutting blade after the last particle of the vegetable 66 has been sliced.

85 In the construction shown in Figure 8, a reinforcing frame 68 is provided having a cross bar 70 which can be engaged by the operator for 15 holding the device while using it. This eliminates any possibility of squeezing the sides 16a of the hopper, which would prevent proper operation of the wall 18a.

90 I have provided a vegetable slicer in which it is not necessary to touch the vegetable after it has been inserted into the hopper. The cutting blade is the movable part of the slicer and since the vegetable feeds by gravity or by the spring urged wall 18a in Figure 8, it is not necessary 25 for the operator to engage the vegetable with his hand and thus run the chance of getting his hand cut.

95 Some changes may be made in the construction and arrangement of the parts of my device without departing from the real spirit and purpose of my invention, and it is my intention to cover by my claims, any modified forms of structure or use of mechanical equivalents, which may be reasonably included within their scope. 35

I claim as my invention:

1. In a vegetable slicer, a frame, a hopper thereon, a slicing blade slidable along said frame and forming one side of said hopper, a slicing knife carried by said slicing blade, opposite sides 40 of said hopper having eyes and a leg member removably received in said eyes.

2. In a vegetable slicer, a frame, a hopper thereon, a slicing blade slidable along said frame and forming one side of said hopper, a slicing 45 knife carried by said slicing blade, opposite sides of said hopper having eyes and a U-shaped leg member having the terminal ends thereof removably received in said eyes.

3. In a slicer of the character disclosed, a 50 frame, a hopper extending from one side thereof, a slicing blade slidable along the opposite side thereof, a slicing knife carried by said slicing blade and a stop for said slicing blade comprising a resilient member anchored at one end, 55 having a projection at its other end and inclined relative to the path of travel of said slicing blade, said slicing blade first engaging the inclined portion thereof and then said projection which positively stops it upon movement of the 60 slicing blade in a direction toward said stop.

4. In a slicer of the character disclosed, a frame, a hopper extending from one side thereof, a slicing blade slidable along the opposite side thereof, a slicing knife carried by said slicing 65 blade and means to arrest and stop the movement of said slicing blade in one direction comprising a spring hook first frictionally engageable and then positively engageable in the hook portion thereof.

5. In a slicer of the character disclosed, a frame, a hopper extending from one side thereof, a slicing blade slidable along the opposite side thereof, a slicing knife carried by said slicing 70 blade and means to stop the movement of 75

said slicing blade comprising a spring hook which can be sprung to a non-stopping position to permit removal of the slicing blade from the frame.

- 5 6. In a slicer of the class described, a substantially rectangular wire frame, a sheet metal hopper on one side thereof having edges encircling said frame, a slicing blade having guide edges partially encircling said edges of said hopper, a slicing knife carried by said slicing blade and a cross bar for the lower edge of said hopper, said cross bar being secured to said frame to prevent longitudinal movement of said hopper relative thereto.
- 10 7. In a slicer of the class described, a substantially rectangular wire frame, a sheet metal hopper on one side thereof having edges encircling said frame, a slicing blade having guide

edges partially encircling said edges of said hopper, a slicing knife carried by said slicing blade and a cross bar for the lower edge of said hopper, said cross bar being secured to said frame in position to terminate one edge of said hopper closely adjacent said slicing knife when it registers therewith, said cross bar reinforcing said edge. 5

8. In a slicer of the class described, a frame, a hopper extending from one side thereof, a slicing blade slidable along the opposite side thereof, a slicing knife carried by said slicing blade, a cross bar for the lower edge of said hopper, said cross bar being secured to said frame in position to terminate one edge of the hopper closely adjacent the slicing knife when it registers therewith, said cross bar reinforcing said edge. 10 15
